DICE ROLLER

Ros Rioux, New York, N. Y.

Application May 3, 1949, Serial No. 2,395

Term of patent 14 years

(Cl. D34—5)

To all whom it may concern:

Be it known that I, Ros Rioux, a Canadian subject, residing at 5 West 63rd Street, New York, in the county of New York and State of New York, have invented a new, original, and ornamental Design for Dice Roller, of which the following is a specification, reference being had to the accompanying drawing constituting a part hereof:

Fig. 1 is a perspective view of a dice roller showing my new design.

Fig. 2 is an end elevational view.

Fig. 3 is a front elevational view.

Fig. 4 is a top plan view.

The drawing figures are lined to indicated transparency.

I claim:

The ornamental design for a dice roller substantially as shown and described.

ROS RIOUX.
